CLAIM

The ornamental design for a constant temperature circulator, as shown and described herein.

DESCRIPTION

FIG. 1 is a isometric front view of the constant temperature circulator;

FIG. 2 is a front view of the constant temperature circulator as shown at FIG. 1;

FIG. 3 is a right side view of the constant temperature circulator as shown at FIG. 1;

FIG. 4 is a left side view of the constant temperature circulator as shown at FIG. 1;

FIG. 5 is a back view of the constant temperature circulator as shown at FIG. 1;

FIG. 6 is a top view of the constant temperature circulator as shown at FIG. 1; and,

FIG. 7 is a bottom view of the constant temperature circulator as shown at FIG. 1.

The broken lines shown in the drawing are for the purpose of illustrating portions of the article and form no part of the claimed design.

1 Claim, 6 Drawing Sheets
